MEANS FOR ADJUSTING HIGH-FREQUENCY
ELECTRIC DISCHARGE DEVICES

William Thomas Gibson, London, England, assignor to International Standard Electric Corporation, New York, N. Y., a corporation of Delaware

Application June 19, 1947, Serial No. 755,599
In Great Britain October 16, 1940

Section 1, Public Law 690, August 8, 1946
Patent expires October 16, 1960

6 Claims. (Cl. 250—27.5)

1

This invention relates to electron discharge devices for operation at high frequencies.

In such devices it is sometimes desirable to provide a metal diaphragm which can be adjustably deformed under the control of means external to the evacuated container or envelope of the discharge device, for the purpose of, for example, tuning a resonator structure contained within the envelope. Where this adjustment is made by mechanical means the obvious construction involves the use of a number of brazed joints which have to hold a vacuum. This involves a difficult construction and, moreover, failure of a brazed joint will cause complete loss of the tube.

It is an object of the invention to provide a means for adjustably deforming a diaphragm in an electron discharge device without the employment of brazed joints. The construction is thereby simplified and manufacturing difficulties reduced.

According to one aspect of the invention a thin metal diaphragm entirely enclosed within the evacuated container is adapted to be moved through the intermediary of a movable member attached to a flexible metal member, such as a bellows, sealed in a glass portion of the container and constituting part of the wall thereof.

The invention is especially applicable to electron discharge devices incorporating hollow resonators within an evacuated container and according to a further feature of the invention such a resonator is tunable by means of a thin metal diaphragm which is located entirely within the vacuum, the container comprising a glass re-entrant stem portion in the length of which is interposed a corrugated metal bellows and which is closed at its inwardly-projecting end by, for example, a glass press, the diaphragm being movable through the intermediary of a member secured to the movable end of the stem portion.

According to a still further feature of the invention, in an electron discharge device of the electron velocity modulated type, a hollow resonator is constituted by a metal tube in the inside of which is provided a pair of spaced apertured metal discs one of which comprises a thin diaphragm, the tube forming part of the wall of the evacuated container end being sealed at one end to a glass bulb to which is sealed a re-entrant stem in the length of which is interposed a corrugated metal bellows and which is closed at its inwardly-projecting end by, for example, a glass press, means being provided adapted to move the inwardly-projecting end of the stem in a direc-

2

tion parallel to the axis of the tube and thereby, through the intermediary of a member connecting the diaphragm and the stem, to deform the diaphragm for the purpose of tuning the resonator.

The above and other features of the invention specified in the appended claims, will be clearly understood from the following description taken in conjunction with the accompanying drawing which is a diagrammatic sectional view of one embodiment of the invention applied to a velocity modulated tube of the Klystron type.

Referring to the drawing, 1 is an outer copper tube which may, if necessary, be cooled by water or air blast or other means. At each end of this tube the copper is flared out as shown at 2 and 3, and turned to a knife edge. To this is sealed a glass bulb by means of a Houskeeper seal.

At the cathode end a stem is sealed, in which carries, for example, a flat cathode 4 heated by an indirect heater, and cylinders 5 and 6 connected by wires to the outside, which can be used at different potentials to form an electrostatic lens system to project the parallel beam of electrons down the whole length of the tube. A disc carrying a piece of tubing 7 all made of copper, and a similar one shown at 8, are brazed on the inside of the tube 1 and together form a hollow resonator. An extension of the tube 8 as shown at 9 constitutes a drift tube in which bunching of electrons occurs, and a similar resonator is built at the other end of this drift tube.

As it is necessary to tune this resonator to the first one, it is necessary to make one part of it deformable. This can be done with diaphragm 10 which carries the tube 11. Diaphragm 10 can be made of very thin copper brazed to the inner tube and the outer tube. The loop of copper wire shown at 12 can be used in known manner to secure feedback between the two resonators, known in order as the buncher and catcher, to provoke oscillations. At the catcher end of the tube, a bulb is sealed on at 3 and into this is sealed a stem which has for part of its length a short section of corrugated copper bellows shown at 14 which is sealed directly to the glass at each end at 15. On the other end is then sealed a press 22 which carries a central wire or rod leading to an electrode 13 which can collect the electrons which pass through the tube.

Upon the stem, and electrically connected to the bellows 14, is mounted a collar which carries a section of copper tube shown at 16. The projecting end of this copper tubing carries a

55

ring 17, the inner edge of which may be threaded, and the outer surface of the tube 11 may also be threaded so that these two members can be engaged by screwing one to the other just before the stem is sealed into the bulb. The electrode connection through the stem is extended in a copper rod 20 which is threaded.

During the exhaust of the tube, which can be carried out through a tubulation 28, the tendency of the bellows 15 to open is controlled by wedging the rod 20 into a fixed position with respect to the end of the bulb by any suitable means. After the exhaust of the tube is complete, a collar 18 is mounted on the outer surface of the bulb, and this carries a metal support 19 upon which a nut 21, which has been threaded on the rod 20, can bear. By this means it is possible to screw down the nut 21 which withdraws the diaphragm 10 towards it, thus effectively carrying out the operation of tuning the resonator. Motion in the reverse direction is automatically carried out when the nut is unscrewed by the air pressure tending to suck the stem inwards.

On the side of the outer tube 1 is mounted a copper tube 24 brazed at 23 to the tube 1. To this at 25 is sealed a piece of glass tubing 26 into which is then sealed a central conductor 27 which ends in a loop projecting into the resonator. This unit forms a coaxial conductor through which the power generated in the hollow resonator may be removed.

In this construction the brazed joint 23 is the only brazed joint in the device which has to maintain a vacuum. The mechanism for moving the diaphragm 10 involves no brazed joints which have to maintain the vacuum.

It is to be understood that the invention is not limited to the embodiment described above in detail nor to the application to electron velocity-modulated tubes. Other applications and modifications coming within the scope of the invention as defined in the appended claims will readily occur to those versed in the art.

What is claimed is:

1. An electron discharge tube of the velocity modulation type comprising an evacuated envelope including a glass stem having a flexible corrugated metal bellows interposed in the length thereof for making a portion of said stem movable with respect to said envelope; a cavity resonator mounted in said envelope; tuning means connected to said resonator and a member secured to said tuning means and to the movable portion of said glass stem.
2. An electron discharge tube of the velocity

modulation type comprising an evacuated envelope including a reentrant glass stem having a flexible corrugated metal bellows interposed in the length thereof and a glass press closing the inwardly projecting end of said stem, said glass press being movable, a cavity resonator mounted in said envelope, a thin metal diaphragm forming a wall for said resonator and means secured to said movable press and to said diaphragm for permitting tuning of said resonator.

3. An electron discharge device according to claim 2 wherein a central grid tube is mounted in an aperture in said diaphragm and said means comprises a metal tube, one end attached to said grid tube and the other end mounted upon said press.

4. An electron discharge device of the velocity modulation type comprising an evacuated envelope including a glass bulb and a reentrant glass stem in said bulb having metal bellows interposed in the length thereof and a glass press closing the inwardly projecting end of said stem, said glass press being movable with respect to said bulb; a cavity resonator in said envelope including a metal tube forming part of said envelope, and being sealed to said glass bulb and a pair of spaced apertured metal discs mounted transversely in said tube, one of said discs being flexible, and a member secured to said press and to said flexible disc to deform said disc in a direction parallel to the axis of said tube to tune said resonator.

5. An electron discharge device according to claim 4 wherein a collecting electrode is mounted upon said press.

6. An electron discharge device of the electron velocity modulated type according to claim 4 wherein said resonator constitutes a catcher resonator and which further comprises a buncher resonator including an extension of said tube and a further pair of spaced and apertured metal discs mounted transversely therein, a wire feed-back loop being provided within said tube between said catcher resonator and said buncher resonator.
